DESIGN FOR A CAP FOR A COLLAPSIBLE TUBE

Rodney B. Osterhoudt, Kingston, N. Y.

Application February 24, 1940, Serial No. 90,489

Term of patent 14 years

To all whom it may concern:

Be it known that I, Rodney B. Osterhoudt, a citizen of the United States, residing at Kingston, in the county of Ulster and State of New York, have invented a new, original, and ornamental Design for a Cap for a Collapsible Tube, of which the following is a specification, reference being had to the accompanying drawing, forming part thereof.

Figure 1 is a view in side elevation of a cap, embodying my design;

Figure 2 is a view in end elevation; and
Figure 3 is a view in top plan.

I claim:

The ornamental design for a cap for a collapsible tube, as shown.

RODNEY B. OSTERHOUDT.
